PROGRESSIVE RELEASE LOCK

William J. Pearson, Los Angeles, Calif.

Application October 23, 1931, Serial No. 570,631

9 Claims. (Cl. 235—130)

This invention relates to progressive release locks designed to be used in conjunction with a parcel post machine printing mechanism, such as disclosed in my co-pending application, Serial No. 367,106, filed May 29, 1929, by William J. Pearson, entitled Parcel post weighing and stamp printing machine, designed to weigh parcel post packages, and to print parcel post stamps of the prepaid meter type; wherein it may be required to print a stamp bearing the name and place of original mailing, the date, the zone number to which the package is addressed, the weight of the package in pounds, the monetary value of the stamp derived from the weight and the zone, a serial number, and such other words, phrases, figures, decorations and designations as it may be desired to print. This mechanism is used in conjunction with a scale, meters, printing mechanism and a paper supply, and may be motor driven and used for printing purposes.

This machine is particularly adapted for the printing of parcel post stamps upon a paper strip which, when cut to the proper stamp length, is delivered from the machine, and, being gummed on the reverse side, may be moistened at the delivery point of the machine and in this condition attached to the package to be mailed. There may be printed a duplicate stamp which may be wound upon a spindle within the machine, or cut to stamp length and delivered with the original stamp.

This machine also provides a novel method of setting up within a machine the mechanical equivalent of a set of numbers put into the machine by an operator by actuation of the keys of the keyboard. In the form of the mechanism herein disclosed, the method of setting up a series of type wheels within the machine includes the requirement that a definite number of key actuations be effected on the keyboard to prepare the machine for a printing operation, whereupon, by means of a control key and the connected motor drive the printing operation may be performed, following which the machine may be cleared and prepared for the next operation. In the form of the machine disclosed there are six numerals to be printed, therefore, one or more keys on the keyboard must be operated to effect a total of six key-actuations before the progressive release lock will be fully operated to allow the printing mechanism to function. Thus it is impossible to print a stamp until the required number of key-actuations has been accomplished, thus reducing to a minimum

the possibility of printing incorrect or mutilated stamps, and the consequent registering of incorrect amounts within the meters of the machine.

This machine includes a registering re-set meter, and a meter actuating mechanism which is set up by the keyboard with the mechanical equivalent of the numbers punched in by means of the keys of the keyboard, and a numeral printing mechanism which is also operated from the keyboard to set up the numbers punched in on the keys. This keyboard comprises ten keys from 0 to 9 inclusive, with the addition of a control key for the operation of the clutch on the power drive, and an error key for clearing the machine. I have provided mechanism whereby the numbers punched in on the keyboard will be successively transmitted by mechanical movement to the printing and metering elements, thus providing a means to set up six different printing numeral wheels with figures from 0 to 9 with only a single bank of ten keys.

An object of my invention is to provide a mechanism whereby a multiple of numbers may be set up in a machine by means of a keyboard comprising only a single bank of ten keys, one or more of these keys being operated repeatedly or successively and in the order which they will assume when printed, and an extension of the same mechanism also transferring the mechanical equivalents of the same numbers to a meter actuating mechanism, which is operated to actuate the meters to register the numbers at the time that a printing operation takes place in the machine; subsequently the machine is cleared of the numerical set-up and prepared for the next operation, with such parts as need to be set for operation re-set in the position necessary for such operation; this includes the selector elements, which transmit the movement originating at the keyboard to the numeral printer and the meter set-up mechanism by successive positions and contacts, making one movement transversely of the travel of the original movement upon the depression of each key or the performance of each key-actuation on the keyboard; also the progressive release lock, which must be set for original position, that it may be rotated one position for each key-actuation on the keyboard until the number of key-actuations corresponding to the number of numerals to be printed have been operated, which, in the machine disclosed is six; whereupon the locking element adjacent the power clutch is released and the machine may be operated for printing

60

100

105

110

- purposes; but should less than six or more than six key-actuations be effected, the lock is not released and the machine must be cleared and the numerals correctly punched in the machine.
- 5 An object of my invention is to provide a means for conducting multiple operations from one source in an orderly and regular manner, wherein a series of progressive movements are initiated from a single source, and wherein there is a simple but positive relation between the initial source of actuation and the elements being acted upon, yet, wherein each of several elements may be acted upon independently from a single source, and wherein a series of progressive movements as initiated from a single source will be governed by the number of movements initiated at the single source in their relation to the ultimate operation of the machine.
- 10 An object of my invention is to provide a control element in the form of a locking mechanism, acting against a clutch releasing member, and which is progressively advanced from an original position by the action of the keys of the keyboard when operated, to a position whereby the lock is released from contact with the clutch releasing member.
- 15 An object of my invention is to provide means whereby the printing elements of the machine may remain inoperative until the proper number of keys has been actuated on the keyboard or until the proper number of key-actuations has taken place, thus preventing the printing of an incorrect stamp and the consequent registering of an incorrect amount in the meter.
- 20 An object of my invention is to provide a progressive release lock which may be re-set to an original position either automatically at the completion of a printing operation, or at any point in its operation at the will of the operator.
- 25 An object of my invention is to provide a control element governing the printing operations of a parcel post machine, comprising a progressive release lock, which, when properly acted upon the correct number of times by the keyboard, when it is operated for setting up a series of numerals within the numeral printer will act to remove from the path of a trip member of the power clutch a retaining means controlled by the progressive release lock, and thus provide an operative relation between the said clutch and the control key upon the keyboard.
- 30 An object of my invention is to provide a control means, for governing the operation of a parcel post machine for printing purposes and particularly the relation between the printing mechanism and the keyboard, wherein it is required that a predetermined number of key-actuations be effected on the keyboard before the control means will be operated to present an operative relation between the connecting parts of the machine for printing purposes; to that end I have provided a rotating member incorporated into the progressive release lock which is rotated step by step at successive operations of the same or different keys on the keyboard, which has contact members so disposed that the progressive rotation of this member will operate to release the power clutch only upon a predetermined number of steps or step movements of the rotating member having been actuated by the keyboard, and which is so constructed wherein should a greater number of steps be actuated by the keyboard than is required a align the mechanism for releasing purposes, the additional step beyond the number required func-

tions to return the mechanism to a relation wherein the releasing member is again in restraining position and thereupon the machine becomes inoperative for printing purposes.

Another object of my invention is to provide means for re-positioning or re-setting the progressive release lock to a starting position wherein the operations of the progressive release lock to functioning position by the step by step movement will coincide step by step with the operations upon the keys of the keyboard; to that end I have provided a re-setting mechanism attached to and operated by the re-setting mechanism of a parcel post machine. The re-setting operation of the progressive release lock may be actuated by an operator through the error key provided on the keyboard; normally if the set-up has been correct and the machine functions properly for a printing operation, the re-setting operation will be taken care of automatically at the completion of the printing operation.

To the above and other objects my invention consists of the novel construction, arrangement and combination of parts as hereinafter fully, clearly and concisely described and definitely pointed out in my claims and illustrated by the accompanying drawings, in which

Fig. 1 is a plan view of the front right-hand portion of a parcel post machine in which is included the various elements which have a direct bearing upon the operation of the release lock, the mechanism of which is disclosed in the upper left-hand corner of this figure.

Fig. 2 is a view in elevation from the left of the portion of the parcel post machine disclosed in Fig. 1, taken approximately on line 2-2 in Fig. 1.

Fig. 3 is a diagrammatic view in plan of the progressive release locking mechanism and its connected parts only, the balance of the parcel post machine shown in Fig. 1 being eliminated to clarify the description of the operation of the progressive release lock; this figure is similar to Fig. 1 in the disclosure of the progressive release lock and its connected parts.

Fig. 4 is a view in elevation from the left similar to Fig. 2, showing diagrammatically the progressive release lock and its connected parts.

Fig. 5 is an elevation partly in section from the left of the re-setting element of the lock, taken approximately on line 5-5 in Fig. 1.

Fig. 6 is an elevation partly in section of the progressive release element as taken from the left on line 6-6 in Fig. 1.

The drawings show a keyboard A having connected thereto a series of key bars B which extend toward the rear of the machine and are attached to the various operative members of the machine for transmitting movement initiated in the keyboard A to other parts of the machine, (not shown), which include a numeral printer, a registering meter, a control meter C, and a meter set-up actuating mechanism D. A selector unit E progressive contacts elements 140 contained in the numeral printer, (not shown), for the purpose of setting up within the machine mechanical equivalents of the numbers punched in on the keyboard A.

After the proper set-up has been made in the machine the printing operation is instituted separately and manually, by means of the control key 10 on the keyboard A; this control key operates the power clutch F which is also controlled by progressive release lock G; the

progressive release lock G is actuated in its progressive movement upon actuation of keys in the keyboard through contact with the butterfly lever unit H, the relation of which to the key bars B is best illustrated in Fig. 3; the actual locking and releasing mechanism is shown at J on both Figs. 1 and 3; the re-setting mechanism of the parcel post machine is represented on these figures by the rock shaft 12.

10 The actuation of the progressive release lock G is instituted by the operation of the keyboard A wherein each one of the keys, as depressed, operates its corresponding key bar B; and as these key bars have a vertical movement and are 15 normally at their upper position, their actuation depresses them and they contact a butterfly lever 13, which is transverse of the path of all of the key bars B; butterfly lever 13 is secured to shaft 14, rockably mounted in supports 15 20 and secured at one end to a rocking lever 16 provided with a bifurcated portion 17 to which is attached, by means of the pin 18, one end of a connecting link 19; the link 19 is attached at its other end to a rocking arm 20, within a bifurcated portion 21, by means of the pin 22; this arm 20 is secured to a rock shaft 23 to 25 which is also secured a rock arm 24 having a bifurcated portion 25 within which is secured, by means of a pin 26, a connecting link 27 attached at its other end, by means of a pin 28, to an arm 29 rockably mounted on shaft 30; the pin 28 has rockably mounted on it a pawl 31 tensioned by a spring (not shown) and adapted to engage teeth 32 of a 30 ratchet wheel 33, thereby providing means to rotate the ratchet wheel 33 one tooth step at a time upon the actuation of one of the keys in the keyboard A. For the purpose of preventing inadvertent reversing of the ratchet wheel 33, I 35 have provided a ratchet dog 34 tensioned by a spring (not shown) and mounted in support 35.

The shaft 30 is rotatably mounted in bearing supports 36 and has secured to it the driven member of the re-setting portion of the progressive release lock, comprising an internal ratchet wheel 37, provided with internal teeth against which operate pawls 38; the pawls 38 are rockably mounted on one face of a driving member 39, which is rotatably mounted upon the shaft 30 and provided with an attached pinion 40 engaging rack teeth 41 of the rack bar 42. This rack bar is secured by pin 43 to arm 44, which in turn is secured to the error rock shaft 12.

55 The ratchet wheel 33 has on one face a pair of diametrically opposed pins 45 and 46. Upon rotation of the ratchet wheel 33, the pins engage a lock bar 47. One end of lock bar 47 is secured to locking bolt 49 adapted to engage a clutch releasing member 50 (Figs. 1 and 2) which engages and operates the trip 51; the trip 51 is adapted to engage a pin 52 which is a part of the clutch-operating mechanism 53 of the clutch F. The lock bar 47 is tensioned against one or the other of the pins 45 and 46 by means of the spring 54; the progressive release lock actuating mechanism comprising the elements disclosed at H and their parts connected to the pawl 31 are tensioned to return, after an actuating movement by means of one of the key bars B, by the tension spring 55; the trip 51 and its connected parts are tensioned toward engaging position by means of the spring 56.

55 The error rock shaft 12 may be operated by a manual operation of the error key 57. The

error key 57 is connected with key bar 58, which bar contacts the roller 59 mounted on rocking arm 60 secured to a shaft 61 mounted at both ends in supports 62. A rocking arm 63 is secured to the shaft 61. A link 65 is secured by pin 64 to the arm 63 and by pin 66 to arm 67 mounted on shaft 12. Upon actuation of the key 57 of the keyboard A the error rock shaft 12 is rocked, thus instituting a clearing action within the machine.

In Fig. 6, a series of positions assumed by the pin 45 during movement of the ratchet wheel 33 are indicated by dotted lines. The position shown in full line for the pin 45 may be termed the initial position, the dotted position 68 the second position, and the following dotted circles the succeeding positions, the position 69 being where the pin first contacts with the locking arm 47; when the pin is at the position 70, the locking arm will have been moved to the dotted line position 71, whereupon the lock 49 will have moved the trip arm 51 out of engagement with the pin 52, thus leaving the clutch ready for operation. The clearing operation of the machine operates through the rock shaft 12 and its connecting rack bar 42 to the pinion 40, which revolves the disc 39 carrying the pawls 38; the pawls 38 are adapted to engage internal ratchet teeth 72 at whatever position they may be at the time of the clearing operation; upon their engagement with the teeth 72 the driven member 37 will be rotated to an original position indicated by the broken lines 73, which represents the completion of the movement for re-setting. In view of the fact that the driven member 37 and the ratchet wheel 33 are secured to the shaft 30 the rotation of member 37 rotates the ratchet wheel 33 an equivalent amount, corresponding to the position at which the driven member 37 was resting when the pawls 38 were 100 rotated and engaged the teeth 72, thereby rotating the driven member 37 to its normal position.

In the description of Fig. 6, the completion of the operation is effected by completion of the movement of rock arm and rack bar 42, by which ratchet wheel 33 is rotated one more notch to bring the pin 45 to the position formerly occupied by the pin 46. Pin 45 will have passed beyond the point of contact with locking arm 47, thus allowing arm 47, under tension of the spring 54, to return to the original position shown in solid lines in Fig. 6.

Should the clearing action be instituted to take place at some point other than where either the pin 45 or the pin 46 will be in the position shown at 70, the pawls 38 will automatically engage the teeth 72 at whatever position they happen to be occupying and rotate the driven member 37 to the original position; this rotation will rotate both of the pins 45, 46 to their original positions, shown in solid lines in Fig. 6. As an illustration, assume that one key of the keyboard has been operated, and that the operator finds he has made an error; assume also that the pin 45 was originally in the full line position shown in Fig. 6, from which point one key-actuation has rotated that pin one notch to the position indicated at 68; therefore, upon the error key 57 being actuated by the operator, the pawls 38, as shown in Fig. 5, will be rotated and engage the teeth 72, rotate the driven member 37, and thereupon rotate the ratchet wheel 33, so that the pin which happens to be in the position 68, will be rotated 110

to the position shown now as occupied by the pin 46 in Fig. 6, thus restoring this mechanism to original functioning position. The pawls 38 automatically return to their starting position 5 upon the return movement of rack bar 42 and rock shaft 12 when error key 57 is released.

In view of the fact that the movement of the parts of the re-setting mechanism is of necessity very rapid, I have provided a brake 74 bearing 10 against the periphery of the driven member 37, which has two positioning notches 75 into which the brake seats at the completion of each operation of re-setting; positioning means for the rack bar 42 are provided by a roller 76 mounted 15 in the frame 36 and bearing against the rack bar 42 to cause it to mesh properly with the pinion 40.

For the purpose of more clearly describing the portions of the parcel post machine illustrated in the drawings it will be seen that the control key 10 in the keyboard A has a connecting means comprising parts 77, 77a and 77b by which it is connected to the latch 78 which it releases from the pin 52 for the purpose of 20 releasing the power clutch F, provided that the trip 51 has previously been properly operated to release the pin 52 for this operation. The power clutch F operates in such a manner that the release of the pin 52 allows the pin 79 25 on the spring-tensioned sliding clutch-operating mechanism 53 to move the member 80 into the path of a cam-operated finger 81 which is continuously operating; finger 81 is driven from the drive shaft 82 and its extensions, whereby 30 the finger 81, while in its inner position (lower than its Fig. 1 position) engages under the projecting portion of member 80 and finger 81 being then moved outwardly (upwardly in Fig. 1) by the cam, carries with it the member 80 to 35 the limit of its movement, determined by its slotted connection with pin 79. This movement of member 80 (upwardly in Fig. 1) operates the bell crank lever system 80a, 80c 80b connected to member 80, and moves into clutch-engaging 40 position the movable member of the clutch which is secured to the bell crank to which member 86 is connected. As this clutch is designed to operate for an interval of time corresponding to a complete rotation of the driven 45 shaft 83, there is provided thereon, by means of the driven gear wheel 84 and a cam face 85, a means to disengage the clutch at a predetermined point in its revolution; when the cam 50 85, engaging one end of the sliding member 55 53, returns it to the position shown in Fig. 1, the pin 52 is engaged by both the trip 51 and the latch 78; this movement returns the sliding member 80 out of the path of the finger 81 and moves the sliding member 86 into the path of 60 the finger 81, which engages under the projecting portion of member 86 and, under the influence of its cam, moves outwardly (upwardly in Fig. 1), carrying member 86 with it and thereby moving the bell crank system to which member 86 is connected to disengage the clutch at 65 this predetermined point.

This clutch operating mechanism is generally similar in construction and mode of operation to the mechanism which forms the subject-matter of a copending application of Henry Nepple, Serial No. 570,636, filed October 23, 1931.

As recited in the statement of invention, the control meter C is of a character required by the Post Office Department for this work, 70 wherein the meter may be set with a prede-

termined monetary amount which may correspond to the amount of postage purchased by a consumer and which, upon the exhaustion of the set amount of postage, will operate to lock the machine against further operation until this meter has again been set. This meter has no direct connection with the progressive release lock in its normal functioning and is completely disclosed in a co-pending application. However, through its function of locking the entire machine, it bears a similar relation to the operations of the progressive release lock, and to that end the locking operation will be described.

Referring to Fig. 1 it will be seen that the highest monetary numeral wheel of the meter wheel train, namely, the meter wheel 87, is provided on one side with a cam face 88, which, upon exhaustion of the amount pre-set in the meter, is moved into contact with the trip 89, which it moves in a lateral direction, thus releasing the drive bar 90 and allowing it to drop; when bar 90 drops the foot 91 comes into the path of the cam 92 secured to a rock shaft 93; this rock shaft 93 is operated at the conclusion 95 of a printing operation to effect a locking operation at the completion of a printing operation, at which time the stamp in process of being printed will have been discharged upon the plate provided for that purpose (not shown); the entire machine will then have been cleared, leaving the entire machine in preparation for the next printing operation upon the re-setting of the meter C and the consequent unlocking of the machine for normal operation. The drive bar 90 100 operates an electric switch (not shown); when the locking operation takes place the electrical switch is operated to open the motor circuit and stop the motor, thus preventing the operation of the machine by motive power. The drive bar 90 also actuates means (not shown) for preventing rotation of the drive shaft 83 and drive mechanism of the machine in one direction, the drive shaft 83 being provided with a nonreverse element, (not shown), which normally prevents 105 operation of the drive mechanism in an opposite direction; thus the drive shaft 83 is positively locked against rotation in either direction.

The movement originating in the keyboard A and transmitted through the key bars B to the selector E is carried through to the other portions of the machine by means of a selector arm 97, which is designed to progressively move laterally to occupy six different successive contact 110 positions to selectively contact and actuate bars, (not shown), of the numeral printer, (not shown); three of the bars, controlling the monetary value printing wheels, have extensions, namely, the bars 98, 99 and 100 (Figs. 1 and 2), which connect through gearing elements 101 to 115 actuate the three elevators 102, 103, 104 and give the stepped portions 105 a movement corresponding to the number of the key operated on the keyboard A to bring the proper numbered step directly beneath the rack bar 106 (Fig. 2); this position of each of these rack bars constitutes a mechanical equivalent of one of the keys as punched in on the keyboard A. This operation comprises the setting up of the numbers within the machine in the set-up mechanism D; 120 actuation of this same mechanism to forward these mechanical equivalent numbers for registration in the meters is accomplished by a driven shaft 107 connected indirectly to the drive shaft 83; during a printing operation a set of cams on 125

80

- shaft 107 (of which one cam 108 is shown in Fig. 2), move the elevator elements vertically, whereupon the step that happens to be situated beneath the rack bar 105 contacts that rack bar 5 and raises it a distance corresponding to the particular step situated thereunder, so that by means of the gearing 109 and the connected shaft 110, the figures are registered within the meter.
- 10 A direct connected set of numeral wheels 111 which indicate to the operator, by a visual reading, the monetary value set up in a set-up mechanism D; these wheels are returned to zero position upon the clearing action of the machine.
- 15 The clearing action of the machine, by operation of the rock shaft 12 also returns the selector E to the original position (shown in Figs. 1 and 2); for that purpose a hook member 112 secured to the rock shaft 12 engages a portion 20 of the selector E to return it to original position. The selector E is controlled in its lateral movement for proper placement by means of a toothed escapement element 113 provided thereunder for the escapement of one tooth at a time, 25 thus providing the step by step progression of the selector E.
- I claim:
1. A device of the character described comprising a keyboard having keys and key-bars associated therewith, a lock-releasing means, a control member engageable with said lock-releasing means for moving said lock-releasing means, means engageable by said keybars for progressively moving said control member, said control member by actuation of one or more of said keys a predetermined total number of times moving said lock-releasing means to lock-releasing position.
2. A device of the character described comprising a keyboard having keys and keybars associated therewith, a rotative member, means engageable by said keybars for rotating said rotative member upon actuation of said keys, a lock-releasing means, and means carried by said rotative member engaging said lock-releasing means for moving said lock-releasing means to lock-releasing position by a predetermined rotation of said rotative member produced by a predetermined number of key-actuations.
3. In a machine of the character described, a keyboard having keys and keybars associated therewith, means for locking the machine against operation, means for releasing said locking means, a rotatable member, means engageable by said keybars and operative to rotate said rotatable member a predetermined degree upon each actuation of a keybar, and means on said rotatable member for engaging and actuating said lock-releasing means by a predetermined number of key-actuations of the same or different keys.
4. In a machine of the character described, a keyboard having keys and keybars associated therewith, a locking member for preventing operation of the machine until a predetermined number of key-actuations have been effected, means for releasing said locking means, a rotatable member, a member engageable by said keybars and connected with said rotatable member to rotate said rotatable member step by step upon actuation of said keybars, and means on said rotatable member engaging said lock-releasing means and for moving said lock-releasing means to lock-releasing position upon
- actuation of said keybars a predetermined total number of times.
5. In a machine of the character described, a keyboard having keys and keybars associated therewith, a locking member for preventing operation of the machine until a predetermined number of key-actuations have been effected, means for releasing said locking means, a rotatable member, a member engageable by said keybars and connected with said rotatable member to rotate said rotatable member step by step upon actuation of said keybars, means on said rotatable member engaging said lock-releasing means and for moving said lock-releasing means to lock-releasing position upon actuation of said keybars a predetermined total number of times, a re-set key on said keyboard, means operable by said re-set key for re-setting said rotatable member to initial position, and spring means for restoring said lock-releasing means to initial position preventing operation of the machine.
6. In a machine of the character described, a plurality of keys having keybars, locking means normally preventing operation of the machine, a slidable member for releasing said locking means, a ratchet wheel, a pawl engaging said ratchet wheel, a rock bar associated with and rockably engageable by each of said keybars upon actuation thereof, connections between said rock bar and said pawl for rotating said ratchet wheel step by step by successive actuation of one or more of said keybars, and a pin fixed to said ratchet wheel for engaging said slidable member and for moving said slidable member to lock-releasing position upon a predetermined total number of key-actuations.
7. In a machine of the character described, a plurality of keys having keybars, locking means normally preventing operation of the machine, a slidable member for releasing said locking means, a ratchet wheel, a pawl engaging said ratchet wheel, a rock bar associated with and rockably engageable by each of said keybars upon actuation thereof, connections between said rock bar and said pawl for rotating said ratchet wheel step by step by successive actuation of one or more of said keybars, a pin fixed to said ratchet wheel for engaging said slidable member and for moving said slidable member to lock-releasing position upon a predetermined number of key actuations of the same or different keys, a restoring key, and operative connections between said restoring key and said ratchet wheel for rotating said ratchet wheel in the opposite direction to restore said slidable member to initial position.
8. In a device of the character described, a keyboard having a plurality of keys and keybars associated therewith, a lock-releasing means, a rotatable member, a rigid bar adjacent to and engageable by each of said keybars and adapted to be moved by actuation of said keybars, means operatively connecting said bar and said rotatable member for rotating said rotatable member a predetermined degree upon each actuation of a keybar and means carried by said rotatable member for engaging and actuating said lock-releasing means upon a predetermined number of movements of said bar by actuations of said keybars.
9. In a device of the character described, a keyboard having a plurality of keys and keybars associated therewith, a lock-releasing member, a rotatable member, a rigid oscillatable bar dis-

posed transversely of said keybars and tiltably engageable by each of said keybars upon the actuation thereof by said keys, means connecting said bar and said rotatable member for effecting a step by step rotation of said rotatable member by successive actuations of one or more of said keybars, and means on said rotatable

member for engaging and actuating said lock-releasing member upon the oscillation of said bar a predetermined number of times by successive key-actuations of the same or different keys.
